UNITED STATES PATENT OFFICE.

HEZEKIAH CONANT, OF HARTFORD, CONNECTICUT.

IMPROVEMENT IN MOLDS FOR CASTING PROJECTILES.

Specification forming part of Letters Patent No. 12,258, dated January 16, 1855.

To all whom it may concern:

Be it known that I, HEZEKIAH CONANT, of Hartford, in the county of Hartford and State of Connecticut, have invented a new and useful Machine for Casting Slugs or Balls of Lead or other Suitable Metal; and I do hereby declare that the following is a full and exact description, reference being had to the accompanying drawings, which form a part of said description.

The machine consists of a wheel, D, (see Figure 1,) made of iron or brass or other suitable material, in the periphery of which the molds are neatly cut in regular order and at equal distances from each other, and in as close proximity as the nature of the metal of which it is composed will allow, as experience shall show. A band, B B, made of similar material, and suitable in thickness, having its interior surface perfectly plain and smooth, is fitted around it, but not perfectly air-tight, and made stationary by being firmly screwed to the top of the two columns C C, and having a portion removed to allow the escape of the slug, as shown at E, when the mold is inverted. Motion is communicated to the wheel D by a toothed wheel or gear O, situated upon the same shaft, (see Figs. 2 and 3,) which is operated upon by a worm or endless screw, X, that being turned by a crank or pulley and band at F, the bearings being properly adjusted and well fitted; also, the thread of the worm fitted well in these parts, through which it moves. The machine is fed from a large ladle, G, Fig. 3, by tube A, of iron, furnished with a stop-cock, K, which is opened and closed by a wrench at L above the plate supporting the ladle. At the lower end of the tube, at A, is inserted a plug, so that in case

of accident the lead may not be allowed to cool in the tube, but can be readily drawn off.

To operate the machine, the required quantity of lead or metal to be cast is placed in G, which is subjected to the heat of fire upon the grates until it is completely fused. The machine being set in motion, then the stop-cock K is turned. The molten lead enters the machine, readily filling each mold as soon as presented, the air either escaping by the small crevice beneath the band or up through the tube into the ladle, the tube being of ample size for that purpose.

Fig. 1 shows a section of part of the molds in process of filling. The wheel D turns as the arrow indicates, and the slugs readily fall out at E. When a sufficient number are cast, and it is desirable to stop the machine, the cock K should be closed first, and when the lead below K has passed out then the machine may be stopped. In this manner an unlimited supply of balls or slugs of limited variety of shape, mostly conical, may be furnished in a short time, from one to two hundred per minute, on a single machine with wheel fifteen inches in diameter containing seventy-five molds.

What I claim as my invention, and desire to secure by Letters Patent, is—

The arrangement of molds in the periphery of a wheel, combined with a stationary band, which also forms part of each mold, the whole operating as above described.

Signed in presence of two subscribing witnesses.

HEZEKIAH CONANT.
